UNITED STATES PATENT OFFICE.

WILLIAM BLAKE, OF BOSTON, MASSACHUSETTS.

IMPROVEMENT IN RETORTS FOR REFINING ZINC.

Specification forming part of Letters Patent No. 39,625, dated August 25, 1863.

To all whom it may concern:

Be it known that I, WILLIAM BLAKE, a resident of Boston, in the county of Suffolk and State of Massachusetts, have made a new and useful invention having reference to Retorts for Refining Zinc or Various Other Metals; and I do hereby declare the same to be fully described in the following specification, and represented in the accompanying drawings, of which—

Figure 1 is a top view, and Fig. 2 a longitudinal section, of a zinc-refining furnace provided with a retort of the improved kind constituting my invention, such retort, when in accordance with my said invention, being furnished with an air-trap or cesspool of induction or one of eduction, or both, the whole being substantially as hereinafter described.

The object of my invention is to prevent the entrance of air into a retort and the oxidation of the zinc by such air during the process of distillation of the zinc, for the purpose of separating it from the iron or other refuse matter with which it may be combined.

In covering or plating iron bars, tubes, sheets, or various other articles of iron with zinc, by means of a zincing-bath or in melting zinc in an iron kettle, the zinc in the bath or in the kettle is liable to and does become more or less amalgamated with iron. The amalgamation or incorporation of the iron with the zinc under such circumstances causes a serious waste of the latter metal, or renders large quantities of it unfit for use in the process of zincing. By means of my improved retort the said amalgam of zinc and iron may have the zinc separated from the iron, and reduced to a state for use.

In the drawings, A denotes an elongated retort made of clay baked or dried to induration. At one end of the said retort there is an entrance or filling passage, a, while at the other end there is an eduction-passage, b. The hole a communicates with or leads out of a trough or vessel, c, applied to the outside surface of the end of the retort. A partition, d, extends across this trough, and has its lower edge at a level above the bottom of the trough and below the inner end of the orifice a. On pouring melted metal or amalgam into the trough, such metal or amalgam will run underneath the partition and rise above the level of its bottom, and flow through the ori-

fice a, and into the retort. The metal or amalgam which will be within the trough during the charging process, and after it may have ceased, will seal the orifice a in a manner to prevent the external air from passing through the trough and such orifice and into the retort. At the rear end of the retort there is also an eduction and condensing trap or cesspool, which in part is a cistern, B, into which the discharge-passage b leads. A partition, e, extends across the said cistern and nearly down to its bottom, and so as to separate the cistern into the chambers f, g, one which (viz., f) is covered, and the other, g, is open at top. The passage b communicates directly with or opens into the chamber f.

The retort is to be set within a furnace, C, of which h may be supposed to represent the grate and i the ash-pit, the heat from the said furnace, when in operation, being supposed to be imparted to the external curved surface of the retort.

The retort, when properly charged with the zinc amalgam, will operate to distil the zinc therefrom, which will pass in fumes or vapors through the passage b and into and be condensed in the cistern B. It will rise to a level in both chambers of the cistern, and when above the bottom of the partition of the cistern, it will prevent the entrance of air into the passage b, and also into the retort, by means of such passage.

The devices—that is, the trough c and its partition d, combined with the filling-orifice—constitute what I term the “induction-cesspool” or “air-trap.” There are other ways in which this cesspool may be constructed, so as to operate substantially as described—as, for instance, the filling-orifice may be arranged at or near the bottom of the end of the retort, and may lead out of a small cistern arranged on the outside of the retort and extending upward beyond the level at which the charge in the retort should ever be suffered to attain. The charge, by flowing into the small cistern, will rise above the level of the passage leading from it into the retort, and will thereby seal such passage so as to prevent the admission of air into and through it and into the retort while the latter may be in operation. The removal of the refined zinc from the eduction trap or cesspool may be effected by ladling it out of the open chamber

thereof, or by a tap-hole made through one side of such chamber.

I claim—

An improved retort consisting of an ordinary retort, A, and a trap or cesspool, as specified, or its equivalent, applied either to the entrance or exit passage of the retort, or to

each of them, and so as to operate substantially as and for the purpose hereinbefore specified.

WM. BLAKE.
